(57) **CLAIM**

The ornamental design for a display screen or portion thereof with transitional graphical user interface, as shown and described.

DESCRIPTION

FIG. 1 is a front view of the first image in a sequence for a display screen or portion thereof with transitional graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is an enlarged view of the claimed portion of FIG. 1, shown separately for clarity of illustration;

FIG. 12 is an enlarged view of the claimed portion of FIG. 2, shown separately for clarity of illustration;

FIG. 13 is an enlarged view of the claimed portion of FIG. 3, shown separately for clarity of illustration;

FIG. 14 is an enlarged view of the claimed portion of FIG.

4, shown separately for clarity of illustration;

FIG. 15 is an enlarged view of the claimed portion of FIG.

5, shown separately for clarity of illustration;

FIG. 16 is an enlarged view of the claimed portion of FIG.

6, shown separately for clarity of illustration;

FIG. 17 is an enlarged view of the claimed portion of FIG.

7, shown separately for clarity of illustration;

(Continued)

FIG. 18 is an enlarged view of the claimed portion of FIG. 8, shown separately for clarity of illustration; FIG. 19 is an enlarged view of the claimed portion of FIG. 9, shown separately for clarity of illustration; and, FIG. 20 is an enlarged view of the claimed portion of FIG. 10, shown separately for clarity of illustration. The outer perimeter shown in broken lines in the figures illustrates a display screen or portion thereof and forms no part of the claimed design. The remaining broken lines in the figures illustrate portions of the graphical user interface that form no part of the claimed design. The appearance of the graphical user interface sequentially transitions between the images shown in FIGS. 1-10. The process or period in which one image transitions to another forms no part of the claimed design.
